UNITED STATES PATENT OFFICE.

FRED MATHEWS, OF CHICAGO, ILLINOIS, ASSIGNEE TO CLINTON C. MURPHY, OF CHICAGO, ILLINOIS.

CAR-DOOR.

1,089,421.

Specification of Letters Patent. Patented Mar. 10, 1914.

Application filed May 4, 1912. Serial No. 895,026.

To all whom it may concern:

Be it known that I, FRED MATHEWS, a citizen of the United States, residing at Chicago, in the county of Cook and State of Illinois, have invented certain new and useful Improvements in Car-Doors, of which the following is a specification.

The object of my invention is to provide an improved door especially adapted for rail-way freight cars and embodying means for effectually protecting the rollers upon which the door is mounted from snow, ice or other matter which might interfere with their free operation, and means for effectually preventing the entrance of snow, rain or other matter to the interior of the car at the upper edge of the door. I have found that these results may be produced in a simple and economical manner by mounting the door rollers upon the car wall instead of in accordance with the more usual practice of mounting the rollers upon the doors. By mounting the rollers upon the car side above the door at one side thereof, it is possible to introduce effectual means for accomplishing the desired results without complicating the mechanism or adding to the cost thereof.

The particular object and nature of the invention will more clearly appear from the following description and claims, taken in connection with the accompanying drawings, in which—

Figure 1 is a side view of the upper part of a portion of a car side showing my invention applied thereto. Fig. 2 is a view similar to Fig. 1 showing part of the structure mounted upon the door broken away. Fig. 3 is a cross sectional view of the structure shown in Figs. 1 and 2, the section being taken at the door opening. Fig. 4 is a sectional view similar to Fig. 3 showing a modified structure; and Fig. 5 is a similar cross sectional view showing another modification.

Upon the side of the car above the door opening and extending to one side thereof a distance sufficient to support the door in its open position, I mount a series of door rollers 1. These door rollers are preferably mounted upon bolts 2 passing through the car wall, in the present instance as shown passing through the sheeting 3 and plate 4. In order to permit the use of a smaller sized bolt, I mount upon the outer projecting end

of each bolt a sleeve 5 which is provided with a shoulder 6. By this arrangement sufficient strength is afforded by the outer end of the bolt 2 and sleeve 5 to support the weight of the car door. The bolt 2 may be provided at its outer end with the usual head 7, a washer 8 being interposed between the bolt head and the outer end of the sleeve 5, and the entire structure being held in place by means of a nut 9 threaded upon the inner end of the bolt 2. This arrangement affords an easy mode of assemblage, the washer 8 being first placed upon the bolt, then the sleeve 5, after which the roller 1 is fitted over the sleeve. The bolt 2 is then inserted through the opening provided therefor in the car wall and the nut 9 threaded thereon to hold the structure in place.

Secured to the upper edge of the door 10 is an angle-iron of some form, that shown in Figs. 1 to 4 being a Z-bar 11 having its lower flange secured to the door by means of bolts 12. The Z-bar is of such dimensions that its central web 12 rests upon the rollers 1 and supports the weight of the door.

In order to hold the door in proximity to the side of the car and to protect the rollers and seal the interior of the car against the entrance of rain, snow or other matter various arrangements may be resorted to. In Figs. 1, 2 and 3 I have shown the upper flange 13 of the Z-bar projecting upwardly in a vertical plane above the door inside of a metal plate 14 secured by means of bolts 15 to the wall of the car above the door and extending to one side thereof. The plate 14 is spaced from the sheeting 3 a sufficient distance to admit the flange 13 of the door Z-bar between said plate and the sheeting. As shown in Fig. 3, the flange 14 is secured to the outer side of the fascia 16. The plate 14 should extend downwardly and overlap the outer side of the flange 13 of the door Z-bar sufficiently to effectually seal the space between the upper edge of the door structure and the upper edge of the door opening, and also to afford a secure hold upon the flange 13 for the purpose of keeping the upper edge of the door in close proximity to the car side. It will thus be seen that the plate 14 or other equivalent structure employed instead thereof serves two functions, namely, protecting the interior of the car and the rollers against

the entrance of snow, ice or other matter, and also holding the upper part of the door in proximity to the side wall of the car.

In Fig. 4 I have shown in place of the flat plate 14 a Z-bar having its upper flange 17 bolted to the car side and projecting over the flange 13 of the Z-bar which is mounted upon the door. In this construction the central web 18 of the Z-bar secured to the car wall overlies the central web of the Z-bar secured to the door and the lower flange 19 of the Z-bar secured to the car wall overlaps upon the outer side of the lower flange of the Z-bar which is secured to the car door.

By this means a more effectual protection of the rollers and interior of the car is secured.

Another modification is shown in Fig. 5 in which a simple angle bar 20 is bolted to the car door 21 and a Z-bar 22 is secured to the car wall above the door opening and extending to the side thereof as in the construction shown in Fig. 4.

All three of the structures described possess the advantages above recited and the

principle of my invention includes all of 25 these arrangements as well as any similar combination of parts.

What I claim is:

A car having a door opening, a series of rollers mounted in the car wall and extending over said opening, a door, a Z-bar having one of its flanges secured to said door adjacent the upper edge thereof, the central web of said Z-bar being spaced above the upper edge of said door and resting on said 35 rollers, and the other flange of said Z-bar extending upwardly adjacent the car wall, a plate secured to said car wall above said door opening and extending downwardly outside of said upwardly extending flange 40 of said Z-bar.

In testimony whereof, I have subscribed my name:

FRED MATHEWS.
